UNITED STATES PATENT OFFICE

CHARLES L. EVERWINE, OF NEWARK, NEW JERSEY

ATTACHMENT FOR INTERNAL COMBUSTION ENGINES

Application filed December 31, 1929. Serial No. 417,797.

The present invention relates to improvements in attachments for internal combustion engines and has reference more particularly to a means for additionally supplying air to the intake manifold whereby to increase the efficiency in the operation of the engines and also tend to eliminate the accumulation of carbon.

A further and important object of the invention is to provide an attachment of the above mentioned character wherein air is admitted to a vacuum container within which is arranged a chemically treated piece of cotton, the air being caused to be forced through the cotton and to become admixed with the chemical, the chemically treated air being discharged through an outlet, a nipple for delivery to the intake manifold of the engine, where the same comingles with the charge entering the manifold from the carburetor.

Another important object of the invention resides in the provision of an attachment of the above mentioned character that includes a balanced valve for association with the outlet nipple of the container so that only the atomized air will be discharged from the container and any overflow will be eliminated by the valve in case too great an air suction occurs.

Another object is to provide an attachment of the above mentioned character that can be readily and easily installed without necessitating any material alteration, the same being at all times positive and efficient in its operation as well as simple in construction, inexpensive, strong and durable.

Other objects and advantages of the invention will become apparent from the following description when taken in connection with the accompanying drawings.

In the accompanying drawings wherein like reference characters indicate corresponding parts throughout the several views:—

Figure 1 is a side elevation of the auxiliary air supply device embodying my invention showing the same mounted on the dash board and connected to the intake manifold of an internal combustion engine.

Figure 2 is a detail elevational view of the attachment per se.

Figure 3 is a top plan view thereof.

Figure 4 is a vertical sectional view taken approximately on the line 4—4 of Figure 2 looking in the direction of the arrows.

Figure 5 is a horizontal sectional view taken approximately on the line 5—5 of Figure 4 looking downwardly, and

Figure 6 is a bottom plan view of the glass jar showing the rod and the jack screw that are provided for maintaining the lid or cover tightly upon the upper open end of the glass jar.

In the drawings wherein for the purpose of illustration is shown a preferred embodiment of my invention, the numeral 1 designates generally my improved auxiliary air supply attachment, the same comprising a cylindrical glass jar 2 that is open at its upper end, the same decreasing gradually in diameter toward its lower end and the bottom of this glass jar is formed with a depression 3 for a purpose to be presently described. A metallic cover 4 is provided for the open upper end of the glass jar 2 and the bottom face of this cover is formed with an annular groove within which is seated a rubber gasket 5 for effecting a seal between the cover and the jar 2. For the purpose of tightly securing the cover on the top of the glass jar, there is provided the rods 6, the same being disposed radially from a hub 7 and being directed upwardly for disposition adjacent the glass jar 2. The upper free ends of these rods are directed inwardly for disposition within suitable apertured ears 8 formed on the top of the cover 4. The hub 7 is formed with a vertical threaded bore 9 to accommodate the threaded lower end of a jack screw 10, the same being formed at its upper end with a head 11 that engages with in the depression 3 formed in the bottom of the glass jar 2. By actuating the jack screw

10 in one direction, a downward pressure will be exerted upon the hub 7 and the rods 6 associated therewith and said rods will cooperate with the cover 4 to force the same tightly in engagement with the upper edge of 100

the jar 2 as obvious from the construction disclosed in the drawings.

An arm 12 extends laterally from the edge of the cover 4 and the outer end of this horizontally disposed arm 12 is adapted to be secured on a supporting bracket 13 that is attached to the dash board A whereby the auxiliary air supply device embodying my invention will be properly mounted on the automobile, the securing means for the arm 12 being shown at 14 in Figures 1, 3 and 4. This construction provides the means whereby the device can be readily and easily attached or removed whenever necessary.

Extending through the cover 4 is an air supply pipe 15, the upper end thereof being formed with an air inlet opening 16 and cooperating with this air inlet opening 16 is a needle valve 17 for regulating the admission of air to the pipe 15. The lower end portion of the pipe is adapted for disposition within the glass jar 2 and terminates at its lower extremity in the upwardly disposed portion 17', and said upwardly disposed portion 17' is formed with an air distributor head 18. This air distributor head includes a series of upwardly pointed teeth 19, the apex portions of which are formed with openings to permit the air to pass therethrough. The teeth 19 constitute a means for retaining the chemically treated cotton 20 that is placed in the glass jar 2 as suggested very clearly in Figure 4. The absorbent material is saturated with a specially formulated non-oily chemical solution known as carbo-vac and consisting of zinc oxide, pick-ris acid, and a combination of alcohol and gasoline as a base. The air passing downwardly in the pipe 15 will be discharged through this absorbent material and will become admixed with vapors rising from the solution to create oxygen gas in the vacuum jar 2. This gas is similar to gas generated when charging a storage battery and when mixed with the charge entering the intake manifold of an engine from the carburetor serves to prevent carbon forming in cylinders of the engine.

The cover 4 is formed with a centrally located outlet opening within which is secured the lower end of the vertical portion of the angular discharge nipple 21 and connected to the discharge end of this nipple is one end of a tube 22, the other end of which enters the intake manifold B of an internal combustion engine C as at 23 with reference more particularly to Figure 1.

Arranged for vertical movement within the vertical portion of the discharge nipple 21 is the balanced valve 24 carried by the upper end of a valve stem 25 that extends downwardly into the glass jar 2. A float 26 is carried by the lower end of this stem 25 while a valve disk 27 is mounted upon the intermediate portion of the valve stem for coopera-

tion with the valve seat 28 formed at the lower end of the opening in the cover 4 within which said discharge nipple 21 is secured.

If too much chemical is poured into the glass jar and rises above the wad of cotton, jolting caused by vibrations of the engine or due to an automobile traveling over a rough road would be liable to cause the liquid to splash upwardly and enter the outlet. This would be objectionable but is prevented due to the fact that the float will rise with the liquid and the valve 27 will temporarily close the outlet. It will thus be seen that the valve and its float act as a check valve to prevent liquid entering the outlet. The valve also acts as a check valve when increased speed of the motor creates an increase intake of chemically treated air and as the float valve is above the cotton and its float left upon the surface of liquid which over-saturates the cotton it prevents the cotton from being sucked-up over the float valve and lodging in the nipple 21.

As heretofore stated, by securing the cover tightly upon the upper edge of the glass jar 2, a vacuum will be created in the glass jar and when the air mixes with the fumes from the saturated piece of cotton, an oxygen gas will be formed and this gas will be discharged from the container 2 into the intake manifold through the tube 22 for admixture with the charge entering the manifold from the carburetor D.

The provision of an auxiliary air supply attachment of the above mentioned character will tend to decrease the accumulation of carbon and to increase the efficiency in the operation of the engine. Furthermore, the simplicity of my device is such as to permit the same to be readily and easily assembled or disassembled for cleaning purposes and the device can be mounted on an automobile without necessitating any material alterations.

While I have shown a preferred embodiment of my invention, it is to be understood that minor changes in the size, shape and arrangement of parts may be resorted to without departing from the spirit of the invention and the scope of the appended claims.

Having thus described the invention, what is claimed as new is:

1. In a device of the class described, an open top container, a cover therefor, a chemically treated absorbent material for disposition within the container, an air supply pipe extending through the cover, an air distributor pipe associated with the lower end of the air supply pipe, perforated teeth extending upwardly from the head for supporting the absorbent material and to cause the air to pass through said material, and an outlet nipple for the chemically treated air extending from the cover.

2. In a device of the class described, an open top container, a cover therefor, a chemically treated absorbent material for disposi-

tion within the container, an air supply pipe extending through the cover, an air distributor pipe associated with the lower end of the air supply pipe, perforated teeth extending upwardly from the head for supporting the absorbent material and to cause the air to pass through said material, and an outlet nipple for the chemically treated air extending from the cover.

3. In a device of the class described, an open top container, a cover therefor, a chemically treated absorbent material for disposition within the container, an air supply pipe extending through the cover, an air distributor pipe associated with the lower end of the air supply pipe, perforated teeth extending upwardly from the head for supporting the absorbent material and to cause the air to pass through said material, and an outlet nipple for the chemically treated air extending from the cover, and additional means for preventing the absorbent material from clogging up the inlet end of said nipple.

4. In a device of the class described, an open top container, a cover therefor, a chemically treated absorbent material for disposition within the container, an air supply pipe extending through the cover, an air distributor head formed on the lower end of the air pipe and adapted to support the absorbent material, and an outlet for the chemically treated air extending from the cover, and means for securing the cover on the container in an airtight manner.

5. In a device of the class described, an open top container, a chemically treated piece of absorbent material for disposition within the container, a removable cover for the top of the container, means for securing the cover in an airtight manner, an air supply pipe extending through the cover, a valved inlet at the upper end of said pipe, an air distributor head formed on the lower end of said pipe for disposition within the lower portion of the container, a series of upwardly extending pointed teeth formed on the distributor head, the apex portions of the teeth being open, said teeth being adapted to support the absorbent material, and a valved discharge nipple for the gas formed in the upper portion of the container when the air passes through the chemically treated absorbent material carried by the cover.

In testimony whereof I affix my signature.

CHARLES L. EVERWINE.
